SANDWICH GRILL

William M. Bardeau, Islington, Ontario, Canada, assignor to John J. Connolly, New York, N.Y.

Filed Jan. 5, 1968, Ser. No. 10,064

Term of patent 14 years

Int. Cl. D7—04

U.S. Cl. D81—10

FIG. 1

FIG. 2

FIGURE 3 is a perspective view of the sandwich grill of FIGURE 1 taken from the front and with the upper platen disposed in a raised position, out of registration with the lower platen thereof; and

I claim:

The ornamental design for a sandwich grill, as shown.
